Attorney, Agent, or Firm—Harold C. Weston

[57] **CLAIM**

The ornamental design for an adjustable pressure relief valve, as shown and described.

DESCRIPTION

FIG. 1 is a perspective view of an adjustable pressure relief valve showing my new design;

FIG. 2 is an elevational view taken from one side thereof, the opposite side being a mirror image of the side shown;

FIG. 3 is a front elevational view thereof;

FIG. 4 is a rear elevational view thereof;

FIG. 5 is a bottom plan view thereof; and

FIG. 6 is a top plan view thereof.

FIG. 2

FIG. 5

FIG. 3

FIG. 6
